Primary Examiner — Stella Reid*Assistant Examiner* — Elizabeth J Oswecki(74) *Attorney, Agent, or Firm* — Husch Blackwell LLP(57) **CLAIM**

The ornamental design for nesting container, as shown and described.

DESCRIPTION

FIG. 1. is a perspective view of the nesting container of the subject invention.

FIG. 2 is a front view of the nesting container of FIG. 1, the left, right side, and rear view being identical thereto.

FIG. 3. is a bottom view of the nesting container of FIG. 1; and,

FIG. 4. is a top view of the nesting container of FIG. 1. In the drawings, the broken lines in FIGS. 3 and 4 depict portions of the design that form no part of the claim.
